UNITED STATES PATENT OFFICE.

THOMAS E. SUFFOLK AND JOSEPH PIGGFORD, OF ELIZABETH, PENNSYLVANIA.

MINER'S SAFETY-LAMP.

1,180,203.

Specification of Letters Patent. Patented Apr. 18, 1916.

Application filed March 20, 1915. Serial No. 15,921.

To all whom it may concern:

Be it known that we, THOMAS E. SUFFOLK and JOSEPH PIGGFORD, citizens of the United States of America, residing at Elizabeth, in the county of Allegheny and State of Pennsylvania, have invented new and useful Improvements in Miners' Safety-Lamps, of which the following is a specification.

This invention relates to improvements in miners' safety lamps and has particular application to a lamp of that type wherein the flame is extinguished by the presence of a gas, thereby preventing an explosion.

In carrying out the present invention, it is our purpose to provide a lamp of the class described wherein the burner casing will be held closed effectively and securely in such manner that the miner will be unable to expose the flame while working in the mine, thereby eliminating the dangers incident to the flame coming into contact with the gas.

It is also our purpose to provide a miners' safety lamp wherein the fuel reservoir will be securely held to the burner casing and which will be constructed in such manner that air may freely enter and leave the burner casing to promote combustion while any gas in the atmosphere surrounding the lamp will be excluded from the interior of the burner casing.

A further object of our invention is to improve and simplify the general construction of miners' safety lamps and to provide a safety lamp which may be worn upon the cap of the miner and which will be light and durable in structure and capable of producing a strong light to facilitate the operation in the mine.

With the above and other objects in view, the invention consists in the construction, combination and arrangement of parts hereinafter set forth in and falling within the scope of the claims.

In the accompanying drawing: Figure 1 is a view in side elevation of a miner's safety lamp constructed in accordance with the present invention. Fig. 2 is a vertical central sectional view through the lamp.

Fig. 3 is an enlarged horizontal sectional view on the line 3—3 of Fig. 2. Fig. 4 is a bottom plan view of one of the baffle plates. Fig. 5 is a cross sectional view therethrough.

Referring now to the drawing in detail, 1 designates a burner casing. This casing

is preferably formed of an inner shell 2 and an outer shell 3 spaced apart a short distance from the inner shell so as to provide an air space between the walls of the burner 60 casing. In the present instance, this burner casing is substantially cup-shaped and the shells 2 and 3 at the open end of the casing are suitably connected to each other and threaded into the casing at the open end 65 thereof is a lens carrier comprising an annulus 4 and a bell 5 formed integral with the annulus 4 and projecting outwardly from the open end of the burner casing 1. Secured within the bell 5 at the junction of the 70 latter with the annulus 4 is a lens 6, while secured within the bell at the outer end thereof is a lens 7 spaced apart from the lens 6.

Formed in the top wall of the burner 75 casing 1 is an opening and disposed within the opening is a circular band 8 formed interiorly with an annular shoulder 9 and disposed within the band 8 and bearing against the under surface of the shoulder 9 80 is a disk of wire gauze 10. This disk of wire gauge is held against the shoulder 9 by means of a baffle plate 11 comprising a circular disk 12 having the periphery thereof formed with an upwardly projecting 85 flange 13, the flange 13 being formed with an inwardly extending flange 14. In practice, the baffle plate 11 is disposed within the annular band 8 at the inner end of the latter and the flange 14 engages the wire 90 disk 10 to hold the latter against the shoulder 9, while the disk 12 is formed with a number of openings 15 through which the products of combustion within the burner casing may pass to the outer atmosphere. 95 Formed on the bottom wall of the burner casing 1 and depending therefrom is a nipple 16 and suitably fastened to the nipple 16 within the burner casing is an appropriate form of burner tip 17, while located 100 in the nipple 16 is a controlling valve 18.

19 designates a fuel reservoir and formed on the upper end of the reservoir 19 is a nipple 20 threaded into the nipple 16, while located in the nipple 20 is a cut off valve 105 21 by means of which the flow of fuel from the reservoir may be stopped.

In the present instance, the side wall of the fuel reservoir 19 is formed with a circular row of notches 22 and engageable 110 with the notches 22 is one extremity of a leaf spring 23, the remaining extremity of

the leaf spring being fastened to the rear wall of the burner casing. By means of this construction, it will be seen that when the nipple 20 on the fuel reservoir 19 is threaded into the nipple 16 and the lower end of the spring 23 engaged with an adjacent notch 22, the fuel reservoir will be held against accidental turning movement relatively to the burner casing. Secured 10 to the rear end wall of the burner casing is a hook 24 whereby the lamp may be secured to the cap of the miner.

In the present instance, one side wall of the burner casing 1 is formed with a sight 15 opening in which is disposed a glass disk 25 and slideable over the glass disk 25 is a plate 26 mounted within suitable guides carried by the side walls of the burner casing. When it is desired to determine the 20 presence of gas the plate 26 is moved to uncover the glass disk 25 and the conduct of the flame issuing from the burner tip 17 noted through the glass 25 so that the presence or absence of an explosive gas may be 25 determined as is well known. When the window formed by the glass disk 25 is out of use the plate 26 is slid to cover the glass disk. In this instance, one side wall of the 30 burner casing is equipped with a sparking device 27 whereby a spark may be thrown across the burner tip 17 when the valves 17 and 21 are opened so as to ignite the gas flowing through the burner tip from the fuel reservoir 19. The bottom wall of the 35 burner casing is formed with an air inlet opening 28 that is protected in a manner identical to the outlet opening in the top wall of the burner casing so as to prevent the entrance of gas to the casing.

40 In accordance with the present invention, we have provided locking devices for the lens carrier and the fuel reservoir respectively so that the miner will be enabled to remove the lens carrier or detach the fuel 45 reservoir from the lamp casing. Thus, the possibility of an explosion due to the carelessness of the miner will be eliminated. The locking devices are magnetically controlled and comprise open ended cylinders 50 29 secured to the wall of the burner casing at the front end thereof and to the nipple 16 respectively. Slidably mounted in each cylinder 29 is a circular armature 30 carrying a pin 31, and formed in the outer wall 55 of the annulus 4 and the similar wall of the nipple 20 are circular rows of notches 32 respectively. The outer end of each cylin-

der 29 is closed by means of a cap plate 33 and interposed between the cap plate 33 and the armature 30 is a coiled expansion spring 60 34 acting to force the pin 31 into an adjacent notch 32. When it is desired to apply the lens carrier and the fuel reservoir to the burner casing, electromagnets are placed in proximity to the armatures 30, thereby sliding 65 the latter against the action of the springs 34 to withdraw the pins 31 from operative position. The annulus 4 of the lens carrier is now threaded into the open end of the burner casing and the nipple 20 threaded into the nipple 16 and when the lens carrier and the nipple 20 are properly positioned the armatures 30 are relieved of the influence 70 of the magnets and the springs 34 react and so slide the pins into the adjacent notches 32. Thus, the lens carrier is locked in position 75 and the fuel reservoir locked to the burner casing in such a manner that the miner cannot obtain access to the burner casing.

80 While we have herein shown and described the preferred form of our invention by way of illustration, we wish it to be understood that we do not limit or confine ourselves to the precise details of construction herein described and delineated, as modification and variation may be made within the scope of the claims without departing from the spirit of the invention.

We claim:

85 A miner's safety lamp comprising a 90 burner casing having an open end and formed of an inner shell and an outer shell spaced apart from the inner shell, a lens carrier carried by the open end of said casing, two lenses in said carrier spaced apart, a 95 nipple depending from said casing, a fuel reservoir connected with said nipple, a burner tip within said casing connected to said nipple, said casing being formed with an inlet opening below the burner tip and an outlet opening above the tip whereby air 100 may be admitted to the casing and the products of combustion discharged from the casing, a disk of wire mesh protecting each opening, and a baffle plate disposed between 105 the disk of wire mesh in the outlet opening and the flame of the burner.

110 In testimony whereof we affix our signatures in presence of two witnesses.

THOMAS E. SUFFOLK.
JOSEPH PIGGFORD.
